2,652,845

COMBINATION PORTABLE BEACH TENT
AND UMBRELLA

Danielle O'Neill and Adolf Ernst, Wildwood, N.J.

Application February 20, 1951, Serial No. 211,822

12 Claims. (Cl. 135—1)

1

This invention relates to a combination portable beach tent and umbrella.

An object of this invention is to provide a combination portable beach tent and umbrella which can be alternately used as a dressing tent or a rain, sun or wind protector.

Another object of this invention is to provide a combination portable beach tent and umbrella which may be quickly set up to provide an enclosure, so that an individual may have privacy while changing from street clothes to a bathing suit and which can be slightly modified to provide an awning or umbrella to protect against direct exposure to the sun, wind or rain.

A further object of this invention is to provide a combination portable beach tent and umbrella which can be quickly collapsed to a comparatively small compact formation for transportation from place to place and for storage.

A still further object of this invention is to provide a combination portable beach tent and umbrella which is provided with ballast to stabilize the tent during adverse weather conditions.

A still further object of this invention is to provide a combination portable beach tent and umbrella which includes an offset support for a centrally disposed umbrella shaft, thereby permitting the occupant to move about within the tent without interfering with the support.

A still further object of this invention is to provide a combination portable beach tent and umbrella which is relatively simple in structure and cheap to manufacture.

The above and still further objects and advantages of the present invention will become apparent upon consideration of the following detailed description of the invention when taken in conjunction with the accompanying drawings, wherein:

Figure 1 is a perspective view of a combination portable beach tent and umbrella constructed according to the present invention, with parts broken away and shown in section;

Figure 2 is a plan view of an enclosure-forming apron forming a part of the combination portable beach tent and umbrella of the present invention;

Figure 3 is an enlarged, sectional view, with parts broken away, taken along the line 3—3 of Figure 2;

Figure 4 is a perspective view of the enclosure-forming apron shown in Figure 2 in a partially collapsed condition;

Figure 5 is a perspective view of the apron 55 being fabricated of a flexible body and formed

2

shown in Figure 4 in a completely collapsed condition and rolled into a substantially cylindrical formation;

Figure 6 is a fragmentary perspective view of a modified form of the combination portable beach tent and umbrella of the present invention;

Figure 7 is a fragmentary plan view of the enclosure-forming apron for use in forming the combination portable beach tent and umbrella shown in Figure 6;

Figure 8 is an enlarged fragmentary sectional view taken along the line 8—8 of Figure 7;

Figure 9 is a fragmentary elevational view taken from the right of Figure 8;

Figure 10 is a perspective view of another modified form of the combination portable beach tent and umbrella of the present invention;

Figure 11 is a fragmentary perspective view of the combination portable beach tent and umbrella shown in Figure 10 in a partially collapsed condition;

Figure 12 is a fragmentary elevational view of a further modified form of the combination portable beach tent and umbrella of the present invention;

Figure 13 is an elevational view, with parts broken away and shown in section, of still another modified form of the combination portable beach tent and umbrella of the present invention;

Figure 14 is an enlarged fragmentary elevational view showing the combination portable beach tent and umbrella of Figure 13 partially folded back to form a sun, wind and rain protector;

Figure 15 is an enlarged fragmentary sectional view showing the offset support for the centrally disposed umbrella shaft of the combination portable beach tent and umbrella shown in Figure 13;

Figure 16 is an enlarged fragmentary detail showing the supporting rings for detachably securing the tent to the collapsible umbrella of the combination portable beach tent and umbrella illustrated in Figure 13; and

Figure 17 is a fragmentary elevational view showing the depending apron of the combination portable beach tent and umbrella shown in Figure 13 completely folded back upon itself.

The several forms of the combination beach tent and umbrella of the present invention each include an upstanding support, an apron dependingly carried by the support, the apron

into an open-ended enclosure with the free side edges confronting each other, suitable means operatively connected to the apron adjacent the lower end thereof for folding the lower end of the apron toward the upper end thereof, and a cover bridging the upper open end of the enclosure and cooperating therewith to form a dressing tent. Suitable structure is provided in each of the embodiments of the invention illustrated for modifying the tent to provide an awning or umbrella to protect a bather against direct exposure to sun, wind, and rain.

Referring now with particularity to Figures 1 to 5, inclusive, there is shown one form of the combination portable beach tent and umbrella, generally designated by the reference numeral 10, and including an upstanding support 11, a depending apron 12 and a cover 13. The support 11 embodies a pair of upright rods 14 and 15 arranged in spaced, parallel relation with respect to each other and each having the lower end thereof adapted for insertion into a supporting surface, such as beach sand. Extending between the rods 14 and 15 contiguous to the upper ends thereof and secured therebetween is a crossbar 16. Arranged intermediate the ends of the crossbar 16 is another crossbar 17 which is mounted on the crossbar 16 at a point intermediate its ends for pivotal movement into and out of a position transversely thereof. In the transverse position, the crossbars 16 and 17 cooperate to define a substantially rectangular supporting frame.

In Figure 2 there is shown the apron 12 utilized in the formation of the combination beach tent and umbrella illustrated in Figure 1. The apron is fabricated of a flexible body 18 which is formed into an open-ended closure with the free side edges 19 and 20 confronting each other. Suitable interengaging means 21 and 22 are carried along the free side edges 19 and 20 for detachably securing the free side edges together. Arranged in end-to-end aligned and spaced relation with respect to each other is a first group of brace or stiffening rods 23 which are supported along the upper end of the body 18. Arranged in end-to-end aligned and spaced relation with respect to each other is a second group of brace or stiffening rods 24 which are secured along the lower end of the body 18. The respective rods 23 of the first group are arranged in spaced, parallel relation with respect to the respective rods 24 of the second group, and define therebetween side panels 25, 26, 27 and 28. As clearly shown in Figure 4, the side panels are foldable into abutting and confronting relation with respect to each other and are rollable into a compact, substantially cylindrical formation for transportation and storage, as depicted in Figure 5. A suitable fabric extension, generally designated by the reference numeral 29, is secured to or formed integrally with the lower end portions of the side panels 25 to 28 and cooperate therewith to form a pocket for the reception of various articles of clothing or ballast, such as sand. In Figure 1 is shown the cover 13 which bridges the open top of the enclosure formed by the side panels 25 to 28, inclusive, the cover 13 being detachably secured to the body 18 by means of the fastening elements 30 and 31 carried by the body 18 and the cover 13. The body 18 is suspendingly supported from the support 11 by any suitable means, such as the hooks 32 carried by the support 11 and the eyes 33 carried along the upper ends of the body 18 contiguous to the corners of the panels 25, 26, 27 and 28. Suitable interen-

gaging elements are provided contiguous to the open mouth of the pocket formed by the extension 29 for constricting the mouth of the pocket, the elements being generally designated by the reference numeral 34.

In actual use, the upright rods 14 and 15 are inserted within a supporting surface. In the event that the rods cannot be inserted into a supporting surface, suitable feet or pedestals may be provided for the rods. The crossbar 17 is then brought into the position illustrated in Figure 1 and the apron 12 is suspendingly supported therefrom. The cover 13 is then extended across the open top of the enclosure formed by the apron 12 and secured thereto by means of the fastening elements 30 and 31. A suitable ballast may be placed into the pockets contiguous to the lower ends of the side panels and the device is ready to receive an individual desiring to change from street clothes to a bathing suit. After changing, the side panels 25 to 28, inclusive, may be folded toward the upper ends thereof and secured in the folded position, wherein the cover 13 and the folded-back flexible body 18 provide an awning or umbrella to protect the bather against direct exposure to sun, wind and rain.

In Figure 6 there is shown a modified form of the combination portable beach tent and umbrella which includes the support 11, the depending apron 12 and a circular cover or canopy 13'. As clearly shown in Figure 7, the brace or stiffening rods 23 carried contiguous to the upper ends of the body 18, in the form of Figures 1 to 5, are replaced by a group of resilient rods 40 which are arranged in end-to-end relation with respect to each other and supported by means of the spaced rings 41 contiguous to and along the upper end of the body 18. Suitable bolt-and-nut assemblies 42 are operatively connected between adjacent ends of the rods 40 for pivotally connecting the rods together for movement into confronting relation with respect to each other. The group of stiffener or brace rods 24 contiguous to the lower end of the body 18, illustrated in Figure 2, cooperate with the resilient rods 40 to define the side panels 43, 44, 45 and 46 which are foldable into abutting and confronting relation with respect to each other just like the panels 25, 26, 27 and 28 of the form of Figures 1 to 5 and shown in Figure 4, and rollable into a compact form, as illustrated in Figure 5 of the form of Figures 1 to 5. The nut and bolt assemblies 42, which are operatively connected to the resilient rods 40, permit the rods to pivot with respect to each other and likewise can effect the securing of the rods in end to end relation, wherein the rods 40 may be bent into a circular supporting frame 48, Figure 6, for the circular canopy or cover 13'. It is to be noted that the free end of the rod 40' is provided with an eye 49 which is detachably engageable about the nut and bolt assembly 42' carried by the resilient rod 40'.

In Figures 10 and 11 there is shown still another modified form of the combination portable beach tent and umbrella of the present invention. In this modification, the flexible apron 12 and cover 13 are suspendingly supported from a support 50 by means of a plurality of suspension cords 51. The support 50 comprises a standard 52 which has one end engageable in the ground, and a hanger arm 53 which projects from the standard 52 and is secured transversely thereof contiguous to the upper end of the standard 52. The hanger arm 53 is braced by means of a bracing

rod or bracket 54 which extends between the hanger arm 53 and the standard 52. The apron 42 is suspendingly supported by means of the cross brace 55 which is detachably connected at one end to a hook, not shown, carried by the apron contiguous to the meeting or facing ends of adjacent brace rods or stiffeners 23 of the apron 42 and cooperates with the rods 23 to form a rectangular supporting frame 56 for the enclosure. The cover 43 is supported in the bridging position on the open end of the enclosure and the suspension cords 51 are connected to the enclosure contiguous to the corners of the supporting frame 56. In Figures 10 and 11, the cover 43 may be secured to one of the side panels of the apron 42. The cross brace 55 is provided at the other end with an eye 57 which is engageable with another hook, not shown, carried by the apron 42 contiguous to the meeting or facing ends of diagonally opposite adjacent rods 23 whereby it can be detachably secured in the position illustrated in Figure 10. To collapse the combination portable beach tent and umbrella illustrated in Figures 10 and 11, the corner of the frame 56 contiguous to the confronting side edges 19 and 20 of the apron 42 is moved toward the opposite corner of the frame 56, as illustrated in Figure 11. The cover 43 can then be folded between the panels 25 and 28, whereupon the panels 25 and 28 can be brought into abutting and confronting relation. The thus folded flexible apron 42 can be rolled into the compact formation illustrated in Figure 5 for transportation and storage.

In Figure 12 there is shown still another form of a combined portable beach tent and umbrella, which includes a collapsible umbrella 60 suspendingly supported from a hook 61 carried contiguous to the free end of the hanger arm 53 of the support 50. An apron 62 is suspendingly supported from the collapsible umbrella 60 and cooperates therewith to form the dressing tent. Any suitable means can be provided for building up and securing the apron 62 in a position wherein the umbrella 60 can be merely utilized as a protector against the sun, rain and wind.

In Figure 13 there is shown still another modified form of the portable beach tent and umbrella of the present invention. In this embodiment, the collapsible umbrella 60, which includes the umbrella shaft 63, the slide sleeve 64, catch spring 65 and the braces 66, is supported by means of a supporting shaft 67 which is offset from the centrally disposed umbrella shaft 63. The supporting shaft 67 includes a pair of sections 68 and 69 disposed in end to end, aligned relation with respect to each other and detachably secured together by means of a collar 70 carried by the section 68 and receiving the section 69. The supporting shaft 67 further embodies a section 71 disposed in end-to-end, aligned relation with respect to the section 69 and connected thereto by means of a collar 72. Arranged intermediate the umbrella shaft 63 and the detachable section 72 of the supporting shaft 67 is a cross shaft 74 which is pivotally connected to the section 71 by the hinge 75 and pivotally connected to the umbrella shaft 63 by the hinge 76. The cross shaft 74 mounts the umbrella 60 for adjustment with respect to the supporting shaft 69 which is laterally offset with respect to the umbrella shaft. Connected between the umbrella and supporting shafts is a brace 77 which is selectively securable to the cross shaft 74 for holding the umbrella in selected positions of its adjustment. As clearly shown in Figure 13, the brace 77 is provided with

a plurality of longitudinally spaced apertures 78 which are adapted to selectively receive the securing elements 79, which is operatively connected to the cross shaft 74 by selectively securing the cross shaft 74 to the brace 77, the umbrella can be held in various positions of its adjustment with respect to the supporting shaft 67. Dependently carried by the umbrella 60 is an apron 80 which cooperates with the umbrella 60 to form the tent. Suitable means are provided for folding the lower end of the apron toward the upper end thereof. As clearly shown in Figure 13, a plurality of longitudinally extending drawstrings 81 are arranged at spaced intervals about the apron 80 and each has one end secured to the lower end of the apron and has the other end actuated interiorly of the enclosure. Each of the drawstrings 81 is guided by a plurality of longitudinally spaced, aligned, guide rings 82 which are movable toward each other upon the application of a pulling force to the drawstring 81. When the drawstrings are pulled, the apron 80 can be brought into the collapsed position, as illustrated in Figure 17, wherein a canopy is formed for shielding the bather from sun or rain. As clearly shown in Figure 16, any suitable means can be provided for suspendingly supporting the apron 80 from the umbrella 60, such as the split clips 83 which are securable to the umbrella 60 by means of the ring 84 and securable to the apron 80 by means of the ring 85. Instead of collapsing the apron 80 into the position illustrated in Figure 17, it may be desirable to partially collapse the apron. As illustrated in Figure 14, the lower end of the apron can be secured contiguous to the upper end thereof, the confronting, folded-back portions of the apron forming a depending skirt for the umbrella 60, the skirt being generally designated by the reference numeral 87.

When actually constructing the combination portable beach tent and umbrella of the present invention, the various aprons and covers may be made of silk, cotton, textile, plastic or other suitable material, while the various supports can be made of metal, wood or suitable plastic. The covers, supports and closure-forming aprons can be detachably secured together by any suitable securing means, such as buttons, hooks and eyes, zippers and the like.

It is readily apparent that numerous other modifications can be made without departing from the spirit of the invention as set forth in the appended claims.

What we claim is:

1. A combination portable beach tent and umbrella comprising an upstanding support, an apron dependingly carried by said support, said apron being fabricated of a flexible body and formed into an open-ended enclosure with the free side edges confronting each other, a group of rods arranged in end to end spaced relation with respect to each other along the upper end of said body and supported thereon, means carried contiguous the lower end of said body and cooperating therewith to form a pocket for the reception of ballast, and a cover bridging the upper open end of said enclosure.

2. A combination portable beach tent and umbrella comprising an upstanding support, an apron dependingly carried by said support, said apron being fabricated of a flexible body and formed into an open-ended enclosure with the free side edges confronting each other, a group of rods arranged in end to end spaced relation with respect to each other along the upper end

of said body and supported thereon, means carried contiguous the lower end of said body and cooperating therewith to form a pocket for the reception of ballast, and a cover bridging the upper open end of said enclosure, and interengaging means along said free side edges for detachably securing said free side edges together.

3. A combination portable beach tent and umbrella comprising an upstanding support, an apron dependingly carried by said support, said apron being fabricated of a flexible body and formed into an open-ended enclosure with the free side edges thereof confronting each other, a first group of rods arranged in end-to-end spaced relation with respect to each other along one end of said body and supported thereon, a second group of rods arranged in end-to-end spaced relation with respect to each other along the other end of said body and supported thereon, the respective rods of said second group being disposed in spaced parallel relation with respect to the respective rods of the first group defining therebetween side panels, said side panels being foldable into abutting and confronting relation with respect to each other and rollable into a compact substantially cylindrical formation, and a cover bridging the upper open end of said enclosure.

4. A combination portable beach tent and umbrella comprising an upstanding support, an apron dependingly carried by said support, said apron being fabricated of a flexible body and formed into an open-ended enclosure with the free side edges thereof confronting each other, a first group of rods arranged in end-to-end spaced relation with respect to each other along one end of said body and supported thereon, a second group of rods arranged in end-to-end spaced relation with respect to each other along the other end of said body and supported thereon, the respective rods of said second group being disposed in spaced parallel relation with respect to the respective rods of the first group defining therebetween side panels, said side panels being foldable into abutting and confronting relation with respect to each other and rollable into a compact substantially cylindrical formation, a cover bridging the upper open end of said enclosure, and means carried contiguous to the lower ends of said panels and cooperating therewith to form a pocket for the reception of ballast.

5. A combination portable beach tent and umbrella comprising an upstanding support, a vertically disposed apron, interengaging means carried by said support and along the upper end of said apron for suspendingly supporting said apron from said support, said apron being fabricated of a flexible body and formed into an open-ended enclosure with the free side edges confronting each other, a group of rods arranged in end to end spaced relation with respect to each other along the upper end of said body and supported thereon, means carried contiguous the lower end of said body and cooperating therewith to form a pocket for the reception of ballast, and a cover bridging the upper open end of said enclosure.

6. A combination portable beach tent and umbrella comprising an upstanding support, an apron dependingly carried by said support, said apron being fabricated of a flexible body and formed into an open-ended enclosure with the free side edges confronting each other, a group of rods arranged in end-to-end spaced relation with respect to each other along the upper end of said body and supported thereon, means carried contiguous the lower end of said body and

cooperating therewith to form a pocket for the reception of ballast, and a cover bridging the upper open end of said enclosure, said support comprising a pair of upright rods arranged in spaced parallel relation with respect to each other, a first crossbar extending between said rods contiguous to the upper ends thereof and secured therebetween, and a second crossbar arranged intermediate the ends of said first crossbar and mounted on the latter at a point intermediate its ends for pivotal movement into and out of a position transverse of said first crossbar.

7. A combination beach tent and umbrella comprising an upstanding support, an apron dependingly carried by said support, said apron being fabricated of a flexible body and formed into an open-ended enclosure with the free side edges thereof confronting each other, a first group of resilient rods arranged in end-to-end relation with respect to each other and supported contiguous to and along the upper end of said body, bolt means operatively connected between adjacent ends of said rods for pivotally connecting same together for movement into confronting relation with respect to each other, a second group of rigid rods arranged in end-to-end relation with respect to each other along the lower end of said body and supported thereon, the respective rods of said second group being disposed in spaced parallel relation with respect to the respective rods of said first group and defining therebetween side panels, said side panels being foldable into abutting and confronting relation with respect to each other and rollable into a compact formation, means operatively connected to said bolt means for detachably securing said first group of rods in end-to-end relation, wherein said first group of rods form a circular supporting frame for said enclosure, means carried contiguous the lower end of said body and cooperating therewith to form a pocket for the reception of ballast, and a cover bridging the upper open end of said enclosure and secured thereto.

8. A combination beach tent and umbrella comprising an upstanding support, an apron dependingly carried by said support, said apron being fabricated of a flexible body and formed into an open-ended enclosure with the free side edges thereof confronting each other, a first group of resilient rods arranged in end-to-end relation with respect to each other and supported contiguous to and along the upper end of said body, bolt means operatively connected between adjacent ends of said rods for pivotally connecting same together for movement into confronting relation with respect to each other, a second group of rigid rods arranged in end-to-end relation with respect to each other along the lower end of said body and supported thereon, the respective rods of said second group being disposed in spaced parallel relation with respect to the respective rods of said first group and defining therebetween side panels, said side panels being foldable into abutting and confronting relation with respect to each other and rollable into a compact formation, and means operatively connected to said bolt means for detachably securing said first group of rods in end-to-end relation, wherein said first group of rods form a circular supporting frame for said enclosure, a cover bridging the upper open ends of said enclosure and secured thereto, means carried contiguous the lower end of said body and cooperating therewith to form a pocket for the reception of ballast, and interengaging means along said free side

edges for detachably securing said free side edges together.

9. A combination beach tent and umbrella comprising an upstanding support, an apron dependingly carried by said support, said apron being fabricated of a flexible body and formed into an open-ended enclosure with the free side edges thereof confronting each other, a first group of resilient rods arranged in end-to-end relation with respect to each other and supported contiguous to and along the upper end of said body, bolt means operatively connected between adjacent ends of said rods for pivotally connecting same together for movement into confronting relation with respect to each other, a second group of rigid rods arranged in end-to-end relation with respect to each other along the lower end of said body and supported thereon, the respective rods of said second group being disposed in spaced parallel relation with respect to the respective rods of said first group and defining therebetween side panels, said side panels being foldable into abutting and confronting relation with respect to each other and rollable into a compact formation, and means operatively connected to said bolt means for detachably securing said first group of rods in end-to-end relation, wherein said first group of rods form a circular supporting frame for said enclosure, means carried contiguous the lower end of said body and cooperating therewith to form a pocket for the reception of ballast, and a cover bridging the upper open end of said enclosure and secured thereto, said support comprising a pair of upright rods arranged in spaced parallel relation with respect to each other, a first crossbar extending between said rods contiguous to the upper ends thereof and secured therebetween, a second crossbar arranged intermediate the ends of said first crossbar and mounted on the latter at a point intermediate its ends for pivotal movement into and out of a position transverse of said first crossbar.

10. A combination portable beach tent and umbrella comprising an upstanding support, an apron dependingly carried by said support, said apron being fabricated of a flexible body and formed into an open-ended enclosure with the free side edges thereof confronting each other, a group of rods arranged in end-to-end aligned spaced relation with respect to each other along one end of said body and supported thereon, a cross brace detachably connected contiguous to the rods of said group and cooperating therewith to form a rectangular supporting frame for said enclosure, means carried contiguous the lower end of said body and cooperating therewith to form a pocket for the reception of ballast, and a cover fabricated of resilient material bridging the upper open end of said enclosure and secured to said flexible body, said cover being foldable between said side panels and said side panels being foldable into abutting and confronting relation with respect to each other and rollable into a compact substantially cylindrical formation.

11. A combination portable beach tent and umbrella comprising an upstanding support, an apron dependingly carried by said support, said apron being fabricated of a flexible body and

formed into an open-ended enclosure with the free side edges thereof confronting each other, a group of rods arranged in end-to-end aligned spaced relation with respect to each other along one end of said body and supported thereon, a cross brace detachably connected contiguous to the rods of said group and cooperating therewith to form a rectangular supporting frame for said enclosure, means carried contiguous the lower end of said body and cooperating therewith to form a pocket for the reception of ballast, and a cover fabricated of resilient material bridging the upper open end of said enclosure and secured to said flexible body, said cover being foldable between said side panels and said side panels being foldable into abutting and confronting relation with respect to each other and rollable into a compact substantially cylindrical formation, said support comprising a standard including an upright rod and a hanger arm projecting from said upright rod contiguous to the upper end thereof and secured thereto.

12. A combination portable beach tent and umbrella comprising an upstanding support, an apron dependingly carried by said support, said apron being fabricated of a flexible body and formed into an open-ended enclosure with the free side edges thereof confronting each other, a group of rods arranged in end-to-end aligned spaced relation with respect to each other along one end of said body and supported thereon, a cross brace detachably connected contiguous to the rods of said group and cooperating therewith to form a rectangular supporting frame for said enclosure, means carried contiguous the lower end of said body and cooperating therewith to form a pocket for the reception of ballast, a cover fabricated of resilient material bridging the upper open end of said enclosure and secured to said flexible body, said cover being foldable between said side panels and said side panels being foldable into abutting and confronting relation with respect to each other and rollable into a compact substantially cylindrical formation, said support comprising a standard including an upright rod and a hanger arm projecting from said upright rod contiguous to the upper end thereof and secured thereto, and a plurality of suspension cords carried by said hanger and connected to said enclosure contiguous to the corners of said supporting frame for suspendingly supporting said enclosure from said hanger arm.

DANIELLE O'NEILL.
